United States Patent Office

Des. 209,333
Patented Nov. 21, 1967

209,333

MUSICAL INSTRUMENT

Julius Ketjen, 701 El Centro St.,
South Pasadena, Calif. 90038

Filed Sept. 23, 1966, Ser. No. 4,003

Term of patent 14 years

(Cl. D56—1)

FIG. 1.

FIG. 2.

FIG. 3.

FIG. 4.

FIG. 5.

FIG. 6.

FIGURE 1 is a top view of a musical instrument, showing my new design;

FIGURE 2 is a side elevational view thereof;

FIGURE 3 is a side elevational view showing the side opposite the side shown in FIGURE 2;

FIGURE 4 is a bottom view thereof;

FIGURE 5 is an end view thereof; and

FIGURE 6 is an end view showing the end opposite the end shown in FIGURE 5.

The dominant features of my new design are shown in solid lines in the drawing.

I claim:

The ornamental design for a musical instrument, as shown and described.
